HOIST

Sidney S. McIntyre, Sedro-Woolley, Wash.

Application November 8, 1943, Serial No. 509,367

5 Claims. (Cl. 254—187)

1

This invention relates to improvements in hoists or winches and it has reference more particularly to what are generally referred to in industry as "hand hoists," and which are suitable for use on ships, docks or at other places for the lifting and handling of loads by a cable that may be wound onto or paid out from a cable drum.

One of the principal objects of this invention is to provide a hand hoist having a frame structure of improved form that facilitates its being mounted, that avoids the placing of strains upon, or causes distortion to parts, due to any unevenness of the foundation, avoids unnecessary friction and gives greater strength to the structure.

Another object of the invention is to provide a hoist of the character stated wherein the cable winding drum is positively driven through intermeshing gears, and wherein a selection may be made of any one of a plurality of gear ratios for driving the drum, as best suits the load being handled or lifted.

It is also an object of the invention to provide a gear driven winch, and to provide for a certain shifting of gears to provide for a free unspooling of cable from the drum when such is desired.

Still another object of this invention is to provide a winch in which the frame structure comprises a fixed, central shaft upon which the cable drum is revolvably mounted, and wherein this shaft is mounted at its opposite ends in independent frames or pedestals which permits them to readily conform to any unevenness of foundation parts to which they may be applied, thus eliminating the usual requirements of extreme accuracy in alining or leveling up of base members on which the hoist is to be mounted, and thus avoiding placing the parts under tension or strain that might otherwise result from drawing the parts down tight with bolts to secure them to parts that are not accurately aligned or leveled up.

Another object of the invention is to provide a novel extension frame coacting with one of the end frames to provide spaced supports for the various gear wheels through which the cable drum may be driven; the gears having hub portions extending from opposite sides and revolvably mounted in the spaced frames, with the gears located, centrally of the hub bearings as a means of cutting down wear and friction. Furthermore, providing a construction that permits use of gears with integrally cast mounting shafts, whereby their weight is reduced and manufacturing costs are lessened.

It is also an object of the invention to provide

5 a hoist of the kind above described wherein the driving gears are equipped for quick and easy application thereto, or removal therefrom of a crank whereby the cable winding drum is to be powered.

Still other objects of the invention reside in the details of construction of various parts, in their combination, and in the mode of operation of the device, as will hereinafter be fully described.

In accomplishing these and other objects of the invention, I have provided the improved details of construction, the preferred forms of which are illustrated in the accompanying drawings, 15 wherein:

Fig. 1 is a side view of a hand hoist or winch embodying the novel features of the present invention.

Fig. 2 is an end view of the same, showing the 20 inner end frame structure and the hub shaft location of the various gears to which the splined stub shaft of the hand crank may be applied for turning the cable drum.

Fig. 3 shows a detail of construction of the 25 outer end support of the hoist frame.

Fig. 4 is a horizontal, sectional view taken on line 4—4 in Fig. 2.

Fig. 4a is a sectional detail, showing the 30 unmeshing of gears for free unwinding of the cable drum.

Fig. 5 is a vertical, cross sectional detail on the line 5—5 in Fig. 4, with parts broken away for better illustration.

Fig. 6 is a sectional detail through one of the 35 driving gears, taken on line 6—6 in Fig. 2.

Fig. 7 is an inside elevation of one of the driving gears of the cable drum, showing the disposition of the brake band therein and the connection of the band with the hand braking lever.

Fig. 8 is an enlarged sectional detail on the 40 line 8—8 in Fig. 7.

Fig. 9 is a perspective view of parts of the 45 braking means.

Fig. 10 is a perspective view of the hand crank for turning the winch drum.

Referring more in detail to the drawings:

The present hand winch comprises a cable winding drum having a cylindrical body portion 5 of suitable length for holding a predetermined length of cable, and equipped at its opposite ends with cable retaining flanges 6 and 7. Mounted on the drum is a cable 8, anchored at its end in the drum, as at 9 in Fig. 4. The drum 5 is equipped within its opposite end portions with coaxial bearings 10—10 in which the drum sup-

porting shaft 12 is revolvably contained; this shaft being mounted at its ends in upright supporting frames, or pedestals, 13 and 14, which hold it rigid and against rotation, and which frames are adapted to be rigidly mounted upon a foundation or support.

The end flange 7 of the drum has a peripheral, cylindrical flange 15 equipped internally with gear teeth, thus to constitute an internal ring gear 18 through which the drum is turned to wind the cable thereonto.

As will be observed best by reference to Figs. 1 and 3, the supporting frame 13 is what is usually referred to as an A frame. At its vertex it is formed with a bearing portion 20 designed to receive one end of the shaft 12 therein. This bearing is longitudinally split at its top side for a purpose present apparent. From the bearing 20, the legs 21-21 of the frame extend downwardly in divergence; these legs being joined by a transverse brace member 22 and being equipped at their lower ends with feet 23 that are bored with holes to receive anchor bolts or the like, as designated at 24 in Fig. 1, whereby to secure the frame to a foundation or support. Ears 25-25' extend upwardly from the bearing at opposite sides of the split or division therein, as seen in Fig. 3, and a clamping bolt 26 is extended through openings in the ears, and carries a nut 26' designed to be tightened, thereby to cause the bearing to be drawn tight about the shaft end therein, thus to hold the shaft against rotation and to render this frame and the shaft relatively rigid.

The frame 14 which is best shown in Figs. 1 and 5, is an upright, transversely disposed structure equipped at opposite ends thereof with feet 28-28 that are bored for reception of anchor bolts 24' to secure this frame rigidly to a base or foundation. This frame has an inwardly extended central bearing 29 in which the adjacent end portion of shaft 12 is fitted and secured by a pin 30, as noted in Fig. 4. At one side of the bearing 29, the frame 14 is formed with a bearing 32 in which a cylindrical hub member 33, which mounts a relatively large power transmission gear wheel 34 thereon, is revolvably fitted and is also longitudinally shiftable a limited distance. At its inner end, the hub member 33 is externally toothed to form a relatively small pinion gear 35 thereon which, by an endwise shifting of the hub member 33, may be moved into and from driving mesh with the internal ring gear 18, as will be best understood by reference to Figs. 4 and 4a.

The gear wheel 34 has a hub portion 34x fitted about the cylindrical hub 33 so that the latter may be shifted endwise therein, but the hub 33 and the wheel 34 are keyed together by a roller key *k* that is set in a longitudinal key slot C in the gear hub 34x as shown in Figs. 4 and 5, thus at all times to maintain a driving connection between parts 33 and 34.

The outer end portion of the hub 33 extends through and beyond the hub 34x of gear wheel 34. This outer end portion, which is designated at 33' in Fig. 4, is revolvably fitted within a bearing 36 that is formed within a supporting frame 37. Frame 37 is upright and is disposed outwardly from and parallel with the frame 14 and is rigidly supported therefrom; this outer frame being hereinafter referred to as the extension frame. The means of support for the extension frame comprises a plurality of legs 37' that are integral therewith and which are extended in-

wardly therefrom and are secured by bolts 38 to the frame 14, as is clearly shown in Fig. 2.

Disposed between the end frame 14 and the extension frame 37 are gear wheels 40 and 41 which are in driving mesh with the gear wheel 34. In the present preferred ratio of parts, the gear 34 has sixty teeth, the gear 40 has twenty-four teeth, and gear 41 has fourteen teeth, while gear wheel 35 has twelve teeth and the internal gear 18 on the drum flange has forty-eight teeth. As will be understood by reference to Fig. 4, the gear wheel 40 has, at its outer face, an outwardly extended, cylindrical hub portion 45 that is revolvably contained in a bearing 46 in frame 37, and at its inner face, has a similar inwardly extended hub portion 47 revolvably contained in a bearing 48 in frame 14. Likewise, the gear 41, see Fig. 6, has tubular hub portions 49 and 50 extending outwardly and inwardly therefrom at outer and inner faces, respectively, and these are revolvably contained in bearings 51 and 52 in frames 37 and 14.

The hub member 33 and the hub portions of the gear wheels 40 and 41 are tubular and it will here be mentioned that the open outer ends of these tubular members open through the outer frame plate 37 for the application of a hand crank thereto for winding in the cable onto the drum.

In the present instance, power is applied to the winch by means of the hand crank, and this power may be applied selectively through any one of the three gears 40, 41 or 35 to obtain the desired gear ratio. The crank used in this instance, as seen in Fig. 10, comprises a lever arm 55 equipped at its outer end with a handle 56. At its inner end, the lever arm is adjustably fixed in a guideway on a block 58 and is adapted to be held at different positions of extension from the block by set screws 59 that are threaded into the block and which may be tightened against the lever.

Fixed to the block 58 is a stub shaft 68 of such diameter that it may be applied coaxially within the cylindrical hub member 33 or within any of the hub portions of the various gear wheels. This stub shaft has a short length thereof 68s adjacent the block 58 enlarged to such diameter that it will form a slip fit within the outer end portion of any of the gear hubs, and this part of the shaft is longitudinally grooved, as at 68g in Fig. 10. Also, each of the tubular hubs has its outer end portion internally splined, and these splines 69 will engage within the grooves 68g of the hub 68 to effect a driving connection between the crank and the gear to which it may be applied.

The grooves 68g are slightly wider than the splines which they receive, and at the open ends, have shoulders 68x restricting entrance thereto. Thus, when turning force is applied to the crank, the shoulders lock back of the ends of the splines to prevent the shaft from being accidentally released.

It is to be noted by reference to Fig. 4, that the inner end diameter of the tubular hubs of the various gears, are reduced to such diameter that when the inner end portion of the stub shaft 68 is applied thereto, it also will have a snug fit, thus to give a longer and more substantial bearing for the shaft.

It will be understood that since the crank 55 with its mounting block 58 and the integral stub shaft 68 may be applied directly to the outer end portion 33' of the hub 33, the drum 5 may then

be rotated through the gear reduction afforded by gears 35 and 18, which is a four-to-one reduction. However, if the crank is applied to the hub 45 of gear wheel 40, then the power is transmitted through gear wheel 40, to wheel 34, then to gear 35 and from this to the driving gear 15, giving a reduction of ten-to-one. Likewise, if the crank is applied to gear wheel 41, then the reduction through gears 41, 34, 35 and 15 is twenty-four to one. It will be understood that the gear wheels 40 and 41 merely idle on the gear wheel 34, when the power is applied directly to gear 35. Furthermore, more gear wheels corresponding to gear wheels 40 and 41, but of different diameter, could be applied to the frames in mesh with gear 34 if additional gear ratios should be desired.

For free unwinding of the drum, it is only necessary to pull the hub member 33 outwardly to the position shown in Fig. 4a, and at which position the gear 35 is entirely disengaged from the internal gear 18. This shifting of the hub member 33 may be effected by hooking a tool within the hub and pulling outwardly, or, when the turning crank is applied thereto, it affords a holding connection due to the fact that the shoulders 68a will engage the ends of the splines. By turning the crank to cause the ends of the splines 69 to mesh with the restricted entrances to the shaft grooves 68g, the crank can be easily pulled out.

It is observed, by reference to Figs. 4 and 4a, that the driving connection between gear 34 and hub 33 is always maintained by reason of the key K.

In order to retard the rate of unwinding of the drum under load, I have provided a brake therefor, as seen in Fig. 7. This brake comprises an internal expanding brake band 70 fitted within the tooth flange of gear wheel 34. One end of the band 70 is anchored to a lug 75 on the end frame 14, as shown in Fig. 5, while the other end is seated within a notch 76 in one end of a lever arm 79 pivoted on one end of a pin 80 that extends through a lug 81 cast on the frame 14. Pivoted on the other end of this pin 80 is an upwardly extended brake lever 83 formed at equal distances from the axial center of the pin 80 with holes 85 which may be selectively registered with a hole 86 in an offset end portion of the lever 79 to receive an attaching bolt 88, as is shown in Figs. 7 and 8. Thus, by means of the lever arm 83, the brake band may be expanded to apply braking pressure to the gear flange. When braking pressure is removed from the lever, a coiled spring 89, attached to the frame and to the free end of the band, draws the band free of the wheel flange.

In order that the drum may be held against unwinding at any set position, I have provided a latch pawl 90 that is mounted on a pivot stud 91 fixed on the frame 14. This pawl has its free end portion positioned to drop into engagement with teeth of gear wheel 34. To release the pawl, there is provided a spring 95 fixed thereto as seen in Fig. 2, which may be moved between notches 96-96' in an arcuate rib on the frame to hold the latch in raised or in engaged position.

On the end of the brake lever, as noted in Fig. 7, and extending beyond the pivot pin 80, is a short foot 83' that will engage the frame to limit the swing of the brake lever 83 toward brake releasing position.

With the parts constructed as described, it will be apparent that in the assembly of the frame, which comprises the shaft 12, end frames 13 and 14, and the extension frame 37, the parts

13 and 14 will readily adjust themselves to unevenness of any foundation on which the hoist is to be attached. Then, after the parts 13 and 14 have been secured to the foundation, the bolt 26 is drawn tight to give support to the opposite end of the shaft, and this renders the whole structure rigid without any strain or tortion being applied to any parts.

It will also be understood that by the particular assembly of the frame 37 on frame 14, as shown, the mounting hubs of gear wheels 40, 41 and 34 will be adequately supported, and in a manner that avoids any unnecessary friction. Furthermore, by making the gear hub portions integral with the gears, weight is reduced and high costs of manufacture avoided.

The provision of the three speed driving gearing gives a range that best suits the operators' ability, and at the same time makes possible the selection of the most practical speed of operation of the drum.

The feature of greatest importance in this assembly is that the strain applied to the winding drum cannot cause any binding, strain or distortion on the gear assemblies, and this is due to the fact that the frame 14 carries the drum shaft and also supports the gears therefrom. Therefore, if there is displacement of the frame 14, all gears are moved accordingly without any change in their relationship.

Having thus described my invention, what I claim as new therein and desire to secure by Letters Patent is:

1. A hoist of the character described comprising, a main frame structure including opposite end pedestals and a cross shaft mounted thereby, a cable winding drum revoluble on the cross shaft having an end flange and a driving gear on said flange coaxial of the shaft, an extension frame member removably fixed to the end pedestal that is adjacent said driving gear and spaced outwardly therefrom, a second gear wheel located between said extension frame member and its supporting pedestal, having hub portions at its opposite sides revolubly mounted in the pedestal and extension frame, a gear pinion integral with the hub portion of the said second gear wheel in driving mesh with the first mentioned gear wheel, a plurality of pinion gears of different diameter located between the extension frame and its supporting pedestal, and having hub portions at opposite sides revoluble in bearings in the extension frame and supporting pedestal; said pinion gears being in driving mesh with the said second gear wheel and said second gear wheel and said plurality of pinion gears each having hub portions exposed through the bearings in the extension frame and a hand crank selectively applicable to any of said portions for the transmission of power to the cable drum.

2. A hoist as in claim 1 wherein each of said gear wheels to which the hand crank is applicable has a tubular hub, and said hand crank has a shaft that is applicable to said hubs in a positive driving connection.

3. A hoist of the character described comprising an end frame adapted for fixed mounting on a support, a drum mounting shaft rigidly fixed at one end in the frame, and extending laterally from one side thereof, a cable winding drum revoluble on the shaft, and having a driving gear thereon adjacent the said end frame, an extension frame fixed to the end frame on the side thereof opposite the drum, and a driving pinion for the drum gear, having a hub portion mounted

by and extending between the said end frame and extension frame for endwise movement to disengage its gear from the drum gear, a driving gear keyed on said hub between the end frame and extension frame, and a driving pinion meshing therewith, and having hub ends mounted in said frames, and means for rotating the last mentioned pinion.

4. In a hoist of the character described, a frame, a shaft fixed in the frame, a cable winding drum revoluble on the shaft having a coaxial driving gear wheel at one end thereof, spaced frame members at that end of the drum, a plurality of trains of power transmission gears of different gear ratio located between the spaced frame members; each train leading to a common gear meshing with the driving gear wheel of the drum; said gears of the gear trains having hub portions revoluble in alined bearings of the spaced frame members and with one end of each hub portion equipped to receive a crank shaft for driving the gear train to turn the drum.

5. A combination as recited in claim 4 wherein said common gear of the several gear trains has a hub member mounted for endwise movement to disengage its gear from the driven gear.

25 SIDNEY S. MCINTYRE.
